UNITED STATES PATENT OFFICE.

WILLIAM F. HELMOND, OF HARTFORD, CONNECTICUT, ASSIGNOR TO UNDERWOOD TYPE-WRITER COMPANY, OF NEW YORK, N. Y., A CORPORATION OF NEW JERSEY.

TYPE-WRITING MACHINE.

No. 904,430.

Specification of Letters Patent.

Patented Nov. 17, 1908.

Application filed May 14, 1908. Serial No. 432,806.

To all whom it may concern:

Be it known that I, WILLIAM F. HELMOND, a citizen of the United States, residing in Hartford, in the county of Hartford and 5 State of Connecticut, have invented certain new and useful Improvements in Type-Writing Machines, of which the following is a specification.

This invention relates to springs employed to press the usual pressure rolls against the revoluble platens of writing machines.

The invention is illustrated in connection with the system of forward and rear pressure rolls heretofore employed in the well-known Underwood front strike writing machines, in which shafts carry the pressure rolls, and arms carry the shafts, the arms being all hinged upon a rod which is rigid 20 upon the platen frame.

One of the principal objects of the invention is to improve the construction, mounting and operation of the springs which press the arms or shafts towards the platen, 25 and to make it feasible to secure any desired pressure at any point of the pressure roll system.

Other objects and advantages will hereinafter appear.

30 In the accompanying drawings, Figure 1 is a bottom view of a platen frame of an Underwood front strike writing machine provided with my improvements. Fig. 2 is an end elevation of the pressure roll system, 35 showing the parts in normal positions. Fig. 3 is a similar view, showing the rolls released. Fig. 4 is an elevation (showing the parts inverted) of one end of a pressure-roll mechanism, showing particularly the manner 40 of securing and adjusting one of the springs. Fig. 5 is a perspective view to illustrate a pair of springs, and other features of the pressure-roll mechanism.

The platen 1 is usually mounted by means 45 of an axle 2 in the ends 3, 4 of a platen frame. Said ends are rigidly connected by a rod 5; and from this rod extend forwardly and rearwardly hinged arms 6, 7, said arms carrying releasably at their extreme ends 50 shafts 8, 9, upon which are mounted forward and rear pressure rolls 10, 11.

At the ends of the rod 5, are rigidly secured blocks or supports 12, said blocks being fixed upon the rod 5 or to the platen

frame; and upon each of these blocks is secured a pair of springs 13, 14, by means of screws 15. The springs extend side by side along the rod 5 and at their ends are formed with fingers 16, 17, which extend along the arms 6, 7 to the ends thereof, and there bear 60 up against said arms to press the rolls 10, 11 against the platen.

A screw 18 passes down through each of the springs, and is threaded into the block 12, to draw said spring down toward the 65 block; each spring being bowed or arched away from the block, as at 19, to give clearance for its adjustment by means of the screws 18. By means of said screws 18, any desired pressure may be put upon either end 70 of either roll shaft 8 or 9, and even running of the rolls and accurate feeding of the paper is thereby secured.

Each of the screws 18 is preferably formed with a square head as shown, and upon its 75 opposite sides each screw is engaged by yielding forks 20, forming a detent, to hold the screw 18 against turning. The detent is in the form of a loop, the head of which is rigidly held between the head of the screw 80 15 and the bottom of the spring 13 or 14. The forks 20 are sufficiently yielding to permit the screw 18 to be turned, but sufficiently strong to prevent it from turning accidentally, so that the tension of the spring 85 13 or 14 is preserved.

It will be seen that springs formed and mounted in this manner, extending side by side along the rod 5, from the ends of the platen frame between the rolls 10, 11, may 90 have sufficient length to give them the required elasticity and flexibility, and also to permit the employment of the described tension-adjusting means. If desired, the springs 13, 14, may be released by turning 95 the screws 18 a predetermined number of revolutions to permit withdrawal of the rolls 10, 11 from the arms 6, 7, without liability of warping or breaking the springs; and upon restoration of the rolls, the tension 100 screws 18 may be turned up the same number of revolutions, thereby restoring the original tension on the rolls. The arms are provided with open slots 21 to detachably receive the roll shafts.

105 Any suitable releasing means may be provided for the pressure rolls, as for instance a key 22, link 23, crank 24 and rock shaft 25,

the latter having flats 26 engageable by release arms 27 formed upon the shaft-carrying arms 6 and 7.

Having thus described my invention, I 5 claim:

1. In a typewriting machine, the combination with a revoluble platen and a platen frame in which the platen is journaled, of forward and rear pressure rolls to 10 run upon the platen, blocks or supports fixed upon the platen frame, a pair of springs secured upon each of said blocks and extending along the platen, to engage means to press the rolls against the platen, and screws 15 passing through said springs and threaded into said blocks to adjust the tension of the springs independently.

2. In a typewriting machine, the combination with a revoluble platen and a platen 20 frame in which the platen is journaled, of forward and rear pressure rolls to run upon the platen, shafts to carry said pressure rolls, independently movable arms in which said shafts are hung, a rod fixed upon said platen 25 frame and carrying said arms, blocks or supports fixed upon the platen frame at the ends of said rod, a pair of springs secured upon each of said blocks and extending along the rod to engage said shaft-carrying 30 arms to press the rolls against the platen, and screws passing through said springs and threaded into said blocks to adjust the tension of the springs independently of one another.

3. In a typewriting machine, the combination with a revoluble platen and a platen frame in which the platen is journaled, of forward and rear pressure rolls to run 40 upon the platen, shafts to carry said pressure rolls, independently movable arms in which said shafts are hung, blocks or supports fixed upon the platen frame, a pair of springs secured upon each of said blocks and extending along the rod to engage said 45 shaft-carrying arms to press the rolls against

the platen, screws passing through said springs and threaded into said blocks to adjust the tension of the springs independently, and yielding detents for the screws.

4. In a typewriting machine, the combination with a revoluble platen and a platen frame in which the platen is journaled, of forward and rear pressure rolls to run upon the platen, independently movable arms for 50 said rolls, blocks or supports fixed upon the platen frame, a pair of springs secured upon each of said blocks and extending along the rod to engage said shaft-carrying arms to press the rolls against the platen, and screws 55 passing through said springs and threaded into said blocks to adjust the tension of the springs independently, the springs being arched or bowed away from the blocks to permit tensioning by said screws.

5. In a typewriting machine, the combination with a revoluble platen and a platen frame in which the platen is journaled, of forward and rear pressure rolls to run upon the platen, shafts to carry said pressure rolls, independently movable arms in which said 70 shafts are hung, a rod fixed upon said platen frame and carrying said arms, blocks or supports fixed upon the platen frame at the ends of said rod, a pair of springs secured side by side upon each of said blocks and extending 75 along the rod, fingers extending laterally from said springs to engage said shaft-carrying arms to press the rolls against the platen, screws passing through said springs and threaded into said blocks to adjust the 80 tension of the springs independently, the screws having square heads, and yielding detents in the form of forks engaging the opposite sides of the screw heads and each secured at one end by a screw which secures 85 the associated spring to the block.

WILLIAM F. HELMOND.
